UNITED STATES PATENT OFFICE.

CORRIE F. RUDOLPH, OF WASHINGTON, DISTRICT OF COLUMBIA.

DESIGN FOR A COMBINATION FAUCET BUBBLING FOUNTAIN.

49,755.

Specification for Design.

Patented Oct. 17, 1916.

Application filed July 12, 1916. Serial No. 108,964. Term of patent 7 years.

To all whom it may concern:

Be it known that I, CORRIE F. RUDOLPH, a citizen of the United States, residing at Washington, in the District of Columbia, have invented a new, original, and ornamental Design for a Combination Faucet Bubbling Fountain, of which the following is a specification, reference being had to the accompanying drawing, forming a part thereof.

The figure is a perspective view of a com-

bination faucet bubbling fountain, showing my new design.

I claim:

The ornamental design for a combination faucet bubbling fountain, as shown.

CORRIE F. RUDOLPH.

Witnesses:

H. L. HARDEE,
F. W. HOUGH.
